UNITED STATES PATENT OFFICE.

ALFRED LINDERSON, OF NORWICH, CONNECTICUT, ASSIGNOR TO DRAPER CORPORATION, OF HOPEDALE, MASSACHUSETTS, A CORPORATION OF MAINE.

SLUB CATCHER FOR SPOOLERS.

Application filed October 12, 1928. Serial No. 312,031.

This invention relates to a device for clearing the yarn or removing the slubs in the operation of a spooler or other similar textile machine.

5 The object of the invention is to provide a simple and practical form of device which will act definitely and positively to clear the yarn.

10 The object of the invention is further to provide such a device which shall be adapted to clear yarns of various sizes.

The object of the invention is further to provide such a device which itself may readily be cleaned.

15 These and other objects and features of the invention will appear more fully from the accompanying description and drawings and will be particularly pointed out in the claims.

Since yarn-clearing and slub-removing devices are well known in connection with spoolers and other similar textile machines it is unnecessary to illustrate and describe a machine to which the device of this invention is applied. All that is shown for that 25 purpose is the usual traverse rod of a spooler upon which the yarn guiding and clearing devices are mounted.

A simple and preferred form of construction embodying the present invention is shown connected to the traverse rod and it is, of course, understood there will be as many of these devices as there are yarns running through the machine.

In the drawings, Fig. 1 is a side elevation of the device;

35 Fig. 2 is a front elevation;

Fig. 3 is a top plan view;

40 Fig. 4 is a detail in elevation showing on an enlarged scale a portion of the lower guide bar;

Fig. 5 is a fragmentary view showing another arrangement of the clearing passage;

45 Fig. 6 is a fragmentary view showing a third arrangement of the clearing passage.

A traverse rod 1 of the ordinary spooler is illustrated as the means for supporting the yarn clearer or slub catcher or remover with which this invention is concerned.

The device as illustrated comprises a two-part bracket, the parts 2 and 3 of which embrace the traverse rod and are clamped thereto by means of the set screw 4 so as to hold the device in the desired working position.

The bracket part 2 carries near its free

end a guide rod 5 extending laterally parallel with the traverse rod 1.

The yarn clearing elements comprise a pair of superimposed guide bars 6 and 7. These guide bars present somewhat extended juxtaposed faces and preferably this result is secured by making each of the bars of substantially square cross section. The lower bar 7 has a shank extending into the bracket part 2 and is locked in place by a set screw 8 threaded into the bracket part. The upper 65 guide bar 6 is pivotally mounted on the lower bar by means of a screw 9 extending therethrough and threaded into the lower bar. This screw 9 has mounted thereon beneath its head a helical spring 10 seated in a recess 70 in the guide bar 6 so that the upper guide bar 6 is held in close contact with the lower guide bar by means of this spring. The two guide bars extend laterally from the bracket part 2 parallel with the traverse rod. 75

A yarn clearing passage is formed between the two guide bars 6 and 7 and preferably as illustrated in Figs. 3 and 4 there are a plurality of these passages of different cross-sectional areas thus to accommodate yarns of 80 different sizes.

In the preferred construction illustrated in Figs. 1 to 4 grooves 10, 11, 12 and 13 are formed in the upper face of the lower bar and extend transversely thereof, these grooves diminishing in diameter, the groove 10 being shown as the largest and the groove 13 as the smallest. When the upper guide bar 6 is closed upon the lower guide bar it will be seen that there are formed a plurality of 90 yarn-clearing passages each of which is bounded by the juxtaposed faces of the two guide bars and that these juxtaposed faces immediately adjacent each passage are in contact thus preventing the passage of yarn between the guide bars except through one of the yarn-clearing passages. 95

Fig. 5 illustrates a construction in which a yarn-clearing passage is formed by the transverse groove 14 entirely in the upper 100 guide bar while Fig. 6 illustrates a form in which the yarn-guiding passage 15 is formed partially in each guide bar but it will be seen that in all cases the result is the same.

With the plurality of yarn-clearing passages it is desirable that means be provided to direct the yarn through a desired or selected yarn-clearing passage. Such a means is

shown as a flat plate 16 having an upstanding projection 17 provided with a guide opening 18. This guide plate is slotted at 19 and adjustably connected to one of the guide bars, as the lower guide bar 7, by means of the set screw 20 so that its guide opening 18 may be brought into alignment with either of the yarn-clearing passages and thus act to direct the yarn therethrough.

- 10 Whenever it is desired to insert the yarn between the guide bars and into one of the yarn-clearing passages and whenever it is desired to remove the yarn or to clean the device from slubs or collections of lint the set screw 9 is released and the upper guide bar 6 swung on the set screw as a pivot to open position as illustrated in Fig. 3.

There is thus presented a very simple, practical and efficient device. Whatever size 20 of yarn may be employed a yarn-clearing passage of suitable size may be selected and the guide plate 16 adjusted to direct the yarn therethrough. The sharp edges of the entrance of the yarn guide passage formed by 25 the superimposed guide bars effectively removes slubs and clears the yarn. There is nothing about the device that is likely to get out of order or to be damaged in use. Whenever necessary any part may easily be replaced 30 as each part is of a simple construction.

Having thus described the invention, what is claimed as new, and desired to be secured by Letters Patent, is:

1. A yarn clearer comprising a pair of 35 superimposed guide bars having a plurality of yarn clearing passages of different cross-sectional area extending transversely of and bounded by the juxtaposed faces of said bars with the said juxtaposed faces immediately 40 adjacent said passages contacting to prevent the passage of the yarn except through said passages.

2. A yarn clearer comprising the construction defined in claim 1 together with yarn-guiding means longitudinally adjustable of 45

said bars to direct the yarn through a selected one of said passages.

3. A yarn clearer comprising the construction defined in claim 1 together with a yarn-guide secured to and longitudinally adjustable of one of said bars to direct the yarn through a selected one of said passages. 50

4. A yarn clearer comprising the construction defined in claim 1, in which there is a pivotal connection between said bars to permit the separation of the juxtaposed faces containing the yarn passages. 55

5. A yarn clearer comprising a pair of superimposed guide bars having a plurality of grooves extending transversely of the upper face of the lower bar, the lower face of the upper bar closing said grooves to form 60 yarn-clearing passages and immediately adjacent said grooves contacting with the upper face of the lower bar to prevent the passage of yarn except through said passages. 65

6. A yarn clearer comprising the construction defined in claim 5 together with a yarn guide secured to and longitudinally adjustable of the lower bar to direct the yarn 70 through a selected one of said grooves.

7. A yarn clearer comprising the construction defined in claim 5 in which the said grooves are of different cross-sectional area and in which a yarn guide is provided, secured to and longitudinally adjustable of the lower bar to direct the yarn through a selected one of said grooves. 75

8. A yarn clearer comprising a pair of superimposed guide bars having a yarn-clearing passage extending transversely of and bounded by the juxtaposed faces of said bars with the said juxtaposed faces immediately adjacent said passage contacting to prevent the passage of the yarn except through said passage. 80

In testimony whereof, I have signed my name to this specification.

ALFRED LINDERSON.
